Application June 26, 1939, Serial No. 281,300

8 Claims. (Cl. 214—59)

The invention relates to distributing mechanism for concrete mixers, and has for one of its objects to provide improved concrete distributing mechanism of the boom and bucket type such as is widely used in connection with paving mixers.

In the laying of concrete roads and streets in accordance with present day practice, the most widely used apparatus is a specialized type of concrete mixer, known as a paver, ordinarily mounted on crawler treads for travel on the sub-grade, and embodying a rotatable drum capable of receiving and mixing batches of a cubic yard or more. It is also customary to provide them with apparatus for distributing the mixed concrete over considerable areas, in the form of a horizontal boom of from 20 to 35 feet in length extending rearwardly from adjacent the discharge opening of the mixing drum and supporting a bucket mounted for reciprocatory traverse thereon. The end of the boom adjacent the drum is pivotally mounted for both horizontal and vertical swinging movements, which may be accomplished at the will of the operator through suitable manual or power operated mechanism; and the bucket is traversed back and forth along the boom by one or more cables, also usually power operated, under the control of the operator.

The buckets are normally of a size sufficient to hold a complete batch from the mixing drum, which they receive from the discharge chute through their open top, and are provided at their bottom with pivoted gates or doors which are retained in closed position by various forms of latches which are capable of being tripped by the operator at will to release the doors and permit the concrete in the bucket to be discharged by gravity through the bottom opening.

In the construction of present day high-speed roadways, the tendency is to eliminate curves as far as possible, or to make them of very long radius. However, it is not always feasible to do this, and when circumstances dictate the construction of a curve in the road of less than a certain radius, it is customary to bank or elevate the outside of the curve. When a paver is working on the sub-grade of such a banked or elevated curve, with its longitudinal axis parallel to the length of the roadway, the paver is of necessity tilted sideways, and since the boom of the distributing mechanism is connected to the paver frame, it also is tilted or canted sideways. In most of the prior constructions, although the buckets have of course been mounted for longitudinal traverse on the booms, no provision has

been made for transverse movements of the buckets relative to the booms, with the result that when such prior pavers were working on banked or elevated curves the buckets were also canted sideways, with consequent undue strain and wear upon the parts, and an increase in the power required to operate them.

It is one of the principal objects of the present invention to provide a construction which will overcome this difficulty, and to this end the invention includes among other things a pivotal suspension of the bucket relative to the boom whereby the latter may tilt or cant sideways while the bucket maintains a perpendicular position.

A further object of the invention is to provide an improved latch mechanism and operating connections for the bucket door, which will accommodate such relative transverse movements between the boom and bucket, and which, while effectively maintaining the bucket door closed until tripped, may be tripped by merely reversing the direction of travel of the bucket towing cable. The door is closed and the latch re-set automatically during the return of the bucket to the mixer drum for a fresh batch by cam means on the boom which co-operate with an angular or bell crank lever constituting a portion of the latch mechanism, which lever carries a plurality of rollers which successively engage with said cam means.

With the above and other objects in view, which will appear as the description proceeds, the invention consists in the novel details of construction and in the novel combinations and arrangements of parts, more fully hereinafter disclosed and particularly pointed out in the appended claims.

Referring to the accompanying drawings forming a part of this specification, in which like reference characters designate like parts in all the views—

Figure 1 is a side elevational view, partly broken away and in section, of the discharge end of a well known form of paving mixer equipped with boom and bucket distributing mechanism constructed in accordance with the present invention, the parts being illustrated in the closed position of the bucket door;

Fig. 2 is an enlarged elevational view, partly in section, of the boom and bucket shown in Fig. 1, as seen from the left of said figure;

Fig. 3 is an enlarged side elevational view, partly in longitudinal section, of the bucket and

a portion of the boom, showing the parts in the tripped or open position of the bucket door;

Fig. 4 is a still further enlarged detail sectional elevational view, taken approximately on the plane indicated by the line 4—4 of Figure 2, looking in the direction of the arrows, and showing the latch mechanism in latched position;

Fig. 5 is a view similar to Fig. 4, but taken approximately on the plane indicated by the line 10 5—5 of Figure 2, illustrating in full lines the parts in their tripped positions, and in broken lines an intermediate position which they assume in the course of the automatic resetting operation;

15 Fig. 6 is a perspective view of the bell crank lever constituting a portion of the door operating and latch mechanism;

Fig. 7 is a perspective view of the towing bracket which is mounted upon the bucket carriage; and

Fig. 8 is a detail perspective view of the latch. Referring more particularly to Figure 1 of the said drawings there is illustrated the discharge end of a typical concrete mixer of the paving type comprising a frame 10 mounted upon crawler treads 11 and having a mixing drum 12 rotatably mounted therein upon rollers 13. Said drum has a discharge chute 14 and sub-chute 15 associated with its discharge opening and said discharge chute 14 may be operated by suitable power means (not shown) in accordance with usual paving mixer practice.

The said mixer also has associated with its discharge end bucket and boom distributing mechanism for the mixed concrete comprising boom 20 here shown as being composed of a pair of horizontally extending spaced channels 21 which are pivotally mounted as at 22 adjacent the end next to the mixer in a caster 23 whereby the boom may be oscillated upwardly and downwardly in a vertical plane by means of block and tackle mechanism 27. The caster 23 is journaled in a vertical bearing 24 carried by a portion of the mixer frame 10 so that the caster and boom may be swung horizontally about the vertical axis by means of a worm gear 25, and worm 26, which latter may be either manually or power operated. One form of mechanism for power operation of this worm is disclosed and claimed in our co-pending application filed June 26, 1939, Serial No. 281,298, entitled Boom swinging mechanism for concrete mixers.

The concrete distributing bucket 30 is mounted by means of a trolley or carriage 31 for longitudinal traverse upon the boom 20 by means of draft cables 32 which extend over suitable pulleys or sheaves 33 to a winding mechanism 34, here shown more or less diagrammatically, of any appropriate construction. An example of power operating mechanism suitable for actuating the cables 32 may be found in our co-pending application filed June 26, 1939, Serial No. 281,299, and entitled Boom and bucket distributing apparatus for concrete mixers.

65 As best shown in Figs. 1, 2 and 3 of the drawings, the bucket carriage 31 may be fabricated from metal plates or sheets and as here shown comprises a plate 35 bent to a channel or U-shape cross section and which is provided upon its outer face with suitable transverse strengthening ribs or webs 36 which may be welded to the channel 35. Each of the upstanding legs of the channel member 35 is provided with a pair of stub shafts 37, one adjacent each end of the channel and 70 projecting inwardly, upon which shafts are jour-

naled the rollers 38 adapted to engage and run upon the lower flanges of the channel members 21 of the boom 20, as will be readily understood from the said drawings.

5 A pivot pin 40 is mounted in a pair of the ribs or webs 36 of the carriage, extending longitudinally of the latter and below the same. Upon this pin is journaled a fabricated transverse suspension structure 41 which is welded or otherwise rigidly secured to the top of the bucket 30 as will 10 be readily understood from Figs. 1, 2 and 3. It thus results that the bucket is pendulously hung from the carriage 31 in such manner as to permit of relative transverse movements between the two.

15 In Fig. 2 the parts are illustrated in the positions they normally occupy when the paver is operating upon level ground, with the longitudinal axis of the boom 20 lying in the vertical plane indicated by the line A. However, should 20 the paver be moved to sloping ground as upon a banked or elevated curve so that it will be tilted sideways, then the longitudinal axis of the boom will likewise be tilted out of the vertical to a plane such as that indicated by either of the 25 lines B of the said figure. However, notwithstanding this transverse tilting of the boom the bucket obviously will maintain a perpendicular position such as that illustrated in Fig. 2 because of its pendulous mounting upon the pivot 30 pin 40 of the carriage 31. This maintenance of the bucket in truly vertical position not only relieves strain and wear upon the parts but also permits of discharge of its contents uniformly across its width rather than having such discharge shifted toward one corner or the other depending upon the direction in which the paver is tilted.

The bucket 30 is provided with an open bottom through which the concrete is discharged by 40 gravity as is customary in such apparatus, and the discharge opening is controlled and normally closed by a gate or door 50 pivoted as at 51 to the bucket. For retaining said door 50 in closed position during filling and outward movement of 45 the bucket the following mechanism is provided. A pair of links 52 are pivotally connected as at 53 to opposite sides of the door 50 and extend upwardly through suitable guides 54 mounted upon the outer face of the side wall of the bucket. The 50 upper end of each link 52 is rigidly connected to a rod 55 which extends through the bottom of a U-shaped strap member 56 the upper ends of which are pivotally connected as at 57 to arms 58 rigidly carried by a transverse shaft 59 which 55 is journaled in suitable bearings 60 mounted upon the forward face or wall of the bucket 30. At the center of the bucket the shaft 59 rigidly carries another pair of arms 61 the outer ends of which are pivotally connected as at 62 to the 60 trunnion member 63 of a universal joint 64. Said universal joint 64 is connected by rod 65 which extends upwardly to a second universal joint 66, the trunnion member 67 of which is pivotally connected as at 68, to the bifurcated arm 69 of a 65 bell crank lever 70. Said lever 70 is pivoted at 71 to a pair of ears 72 rigidly carried by the carriage 31. The said bell crank lever is further provided with an angularly extending bifurcated arm 73, which journals a pair of rollers 74 and 75 70 substantially as shown. The said bell crank 70 is further provided with an inclined rigid finger 76 extending in a plane substantially parallel to that of the arm 73, as will be readily understood from Figures 4, 5 and 6.

Rigidly mounted upon the carriage 31 in co-operative relation to the bell crank 70 is a towing block 80 which, as will be readily understood from Fig. 7, comprises a base member 81 and a pair of spaced longitudinal extending ribs 82 which extend outwardly above the ears or lugs 72 on the front face of the carriage and each of which is provided with a pair of spaced laterally extending lugs or projections 83 and 84, which are oppositely inclined substantially as shown. A pair of draft links 86 is pivotally mounted upon the pin 71 which supports the bell crank, which links extend upwardly within the spaces between the lugs 83 and 84 of towing block 80 as clearly shown in Figs. 2, 3 and 4. The upper ends of these draft links 86 embrace and are pivotally connected as at 87 to a suitable cable connector 88 by means of which the draft cables 32 are connected to the said links.

26 A latch member 90 is pivotally mounted as at 91 between the draft links 86 intermediate their ends, which latch as best shown in Figs. 4 and 8, is recessed as at 92 to provide a toe 93 which is adapted to engage with the finger 76 of the bell crank lever 70, as clearly shown in Fig. 4.

Going back to the links 52 and the U-shaped strap member 56 of the bucket door operating and controlling mechanism, the rods 55 which extend upwardly from the links 52 are surrounded by helical springs 100 which are confined between the closed end of the strap member 56 and a plate or seat member 101 which is slidably mounted within the U-shaped strap 56. Said springs 100 are pre-loaded or compressed by means of the adjusting nut 102 to a point sufficient to withstand the weight of any batch of concrete which the bucket may hold so that the door will be maintained tightly closed at all times, except when the latch mechanism has been tripped, as will be hereinafter explained. The said links 52 are also provided with adjustable stop members 104 which may be positioned at different points along the length of the links by means of the series of openings 105 provided in the said links for the reception of the pins 106 by means of which the stop members 104 are secured to the said links. These stop members 104 are adapted to engage rubber or other resilient buffers 107 which normally rest upon the flanges of the 50 guide members 54 and thereby cushion the shock of the opening of the bucket door as will be readily understood. By adjusting the position of the stops 104 the degree of opening of the door may be controlled.

55 In operation when the bucket is at the inner end of the boom in position to receive a batch of concrete from the drum 12, the latch and door controlling mechanism are in the positions illustrated in Figs. 1, 2 and 4, with the toe 93 of the latch 90 in engagement with the finger 76 of the bell crank 70. In this condition if the draft cable 32 be operated by the mechanism 34 to move the bucket toward the left as viewed in Fig. 1, or toward the right as viewed in Fig. 4, the motion will be transmitted through the connector 88 and pivotal connections 87 to the draft links 86, which being in engagement with the lugs 83 of the towing block 80, will draw the carriage 31 and consequently the bucket 30 in the 60 directions above indicated. This traverse of the carriage and the bucket along the boom will continue until the point has been reached at which it is desired to discharge the contents of the bucket, whereupon by causing the winding mechanism 34 to reverse the direction of travel of the

5 draft cable 32 the reversed motion thereof will be transmitted through the connector 88 and pivotal connections 87 to the draft links 86 which will cause the latter to swing in a counterclockwise direction as viewed in Fig. 4, until they engage 5 the lugs 84 of the towing block 80 which position is illustrated at Figs. 3 and 5. During this movement of the draft links 86, which is lost motion so far as bucket traverse is concerned, the latch 90 has, through its engagement with the finger 10 76 of the bell crank 70, caused the latter to move in a counterclockwise direction about its pivot 71. It will be noted from Fig. 1 that in the normal closed position of the door 50 the pivot 68 of the universal joint 66 lies to the right of a straight 15 line between the pivot 71 of the bell crank and the pivot 62 of the lower universal 64, so that a toggle action is had which resists the tendency of the door 50 to open under its own weight or that of the bucket contents. That is to say, in 20 the position shown in Figs. 1 and 4 any tendency of the door to open and thus move the links 52 and straps 56 downwardly and the arms 61 and rods 65 upwardly tends to cause a counterclockwise rotation of the bell crank 70 as viewed in 25 Fig. 1, or a clockwise rotation of it as viewed in Fig. 4, which tendency however will be overcome by reason of the engagement of the arm 69 of the bell-crank lever 70 with a stop block or member 109 carried by the end rib 36 of the carriage 31. 30 It therefore follows that the bell crank can not be rotated in this direction to permit the door to open under the weight of the concrete in the bucket.

35 However, when the bell crank lever 70 is positively moved in a clockwise direction, as viewed in Fig. 1, during the lost motion movement of draft links 86 from lugs 83 to lugs 84, as above described, the pin 68 of universal joint 66 will be moved to the left of the dead center or straight 40 line between pins 62 and 71, thereby breaking the toggle, and as soon as this is done the tendency of the door and lower connections to move the bell crank counterclockwise is reversed and the weight of the door and the bucket contents now 45 tends to continue the clockwise movement of the bell crank which has been initiated by the latch 90 and draft links 86. As a result, the door drops by gravity to the position shown in Fig. 3, discharging the bucket contents, and in so dropping 50 moves the bell crank 70 and its associated parts to the positions shown in full lines in Fig. 5. During discharge of the bucket contents the bucket may be traversed along the boom 20 in either direction by causing the winding mechanism 34 to move the cables 32 in the desired direction, thus permitting the concrete to be spread over a considerable area instead of being dumped in a heap. Such motion of the cables 32 will be transmitted to the carriage 31 by the draft links 60 86 and lugs 83 or 84 of the towing bracket 80, but will have no effect upon the bell crank 70 or the door 50 until they are reset.

65 For closing the door 50 and re-setting the latch mechanism, cam means, here shown as comprising angle brackets 110, 111 and 112 are provided upon the inner face of one of the boom channels 21 adjacent the inner end of the boom so that the door will be automatically closed and the latch re-set as the bucket approaches its receiving 70 position. These angle or cam members, as best shown in Figs. 2 and 5, are in position to be engaged by the rollers 74 and 75 carried by the arms 73 of the bell crank 70.

75 After the parts have been tripped to open the 75

bucket door as just described above, they are in the position shown in full lines in Fig. 5. If now the movement of the draft cable 32 be continued toward the left as viewed in said figure to draw 5 the bucket inwardly along the boom toward its receiving position, the roller 75 will be brought into contact with the downwardly inclined surface of the cam or angle member 110 as shown in full lines in said figure, and as movement of 10 the parts toward the left continues such engagement will cause partial rotation in a clockwise direction of the bell crank lever 70 about its pivot 71. This rotation will in turn bring the roller 74 in position to engage the more steeply inclined 15 face of the cam or angle member 111, as indicated in broken lines in Fig. 5, and as the draft movement of the cable 32 continues the parts will ultimately be restored to the positions shown in Figs. 1 and 4. As the bell crank 70 moves in 20 the clockwise direction during the re-setting operation its finger 76 automatically enters the recess 92 of the latch 90 and is brought into engagement with the toe 93 of the said latch as the parts reach the closed position of the bucket 25 door.

In the innermost position of the bucket, in which it receives the concrete from the discharge chute 14, the roller 74 is under the angle member 112 on boom 20, which prevents unintentional 30 tripping of the bell crank 70 and opening of the door so as to discharge the concrete in this close-in position.

As above indicated, the springs 100 which are interposed between the bottom of the U-shaped 35 strap members 56 and the spring plates 101 are pre-loaded or compressed sufficiently to withstand the weight of any batch of concrete which may be within the bucket. The parts are so constructed and arranged that during the closing 40 movements of the door 50 it reaches its seated position against the bottom of the bucket slightly before the bell crank 70 and its associated parts have reached the toggle-locked positions shown in Figs. 1, 2 and 4. As the bell crank continues 45 its movement after the door is thus seated its motion is transmitted through the universal joint 66, connecting rod 65, universal joint 64, arms 61, shaft 59 and arms 58 to the strap members 56, and since the door 50 and links 52 can move 50 no further in an upward direction the strap members 56 cause a further compression of the springs 100. The purpose of this is to accommodate or 55 compensate for relative movements between the bucket and carriage about the pivot pin 40. That is to say, since the bucket is not in any ways restrained against swinging upon the pivot pin, even though the paver and boom may not be tilted sideways, when such swinging movements of the bucket take place during its outward 60 travel, they will have a tendency to cause clockwise movement of the arms 61 and 58, as viewed in Fig. 1, which is the direction in which these arms move as the bucket door opens, and if the connections between the arms 58 and the door 65 50 were rigid the latter would be slightly opened and permit leakage at least of the more liquid constituents of the mixture. However, with the provision of the pre-loaded springs 100 should such movement of the arms 58 and 60 occur by 70 reason of swinging of the bucket upon the pivot pin 40 the springs will expand and maintain the door tightly closed and thus prevent such leakage.

While one form of the invention has been illustrated and described it is obvious that those 75 skilled in the art may vary the details of con-

struction as well as the precise arrangement of parts without departing from the spirit of the invention and therefore it is not wished to be limited to the above disclosure except as may be required by the claims.

What is claimed is:

1. Mechanism for actuating the discharge-controlling door of the distributing bucket of a concrete mixer, said bucket being attached to a carriage traversable upon a boom extending from the mixer frame and subject to transverse canting movements thereof, there being a longitudinal pivotal connection between the bucket and carriage to accommodate said canting movements of the boom while the bucket remains perpendicular; said mechanism comprising a lever pivoted upon the carriage and provided with means engageable during traverse of the carriage upon the boom with a portion of the boom to impart movement to the lever; thrust-transmitting linkage carried by the bucket, extending from said lever to the bucket door and connected therewith; and a pivotal connection between said linkage and lever disposed adjacent the longitudinal pivotal connection between the bucket and carriage. 25

2. Mechanism for actuating the discharge-controlling door of the distributing bucket of a concrete mixer, said bucket being pendulously pivotally connected to a carriage traversable upon a boom extending from the mixer frame and subject to transverse canting movements of the latter, the axis of said pivotal connection extending longitudinally of said boom whereby the bucket may maintain a perpendicular position when the boom cant transversely; said mechanism comprising a substantially L-shaped lever pivotally mounted upon the carriage, one arm of which is provided with means engageable during traverse of the carriage in one direction with a boom-carried element to impart movement to the lever in one direction; thrust-transmitting linkage carried by the bucket, extending from said lever to the bucket door and connected to the latter; and a universal pivotal connection between said linkage and the other arm of said lever disposed adjacent the longitudinal pivotal connection between the bucket and carriage, whereby to accommodate the transverse canting movements of the boom relative to the bucket. 35

3. Mechanism for actuating the discharge-controlling door of the distributing bucket of a concrete mixer, said bucket being pendulously pivotally connected to a carriage traversable by reciprocating means upon a boom extending from the mixer frame and subject to transverse canting movements of the latter, the axis of said pivotal connection extending longitudinally of said boom whereby the bucket may maintain a perpendicular position when the boom cant transversely; said mechanism comprising a substantially L-shaped lever pivotally mounted upon the carriage, one arm of which is provided with means engageable during traverse of the carriage in one direction with a boom-carried element to impart movement to the lever in one direction; linkage 40 carried by the bucket, having a portion thereof connected to the bucket door; a pivotal connection between another portion of said linkage and the other arm of said lever, disposed adjacent the longitudinal pivotal connection between the bucket and carriage, whereby to accommodate the transverse canting movements of the boom relative to the bucket; a finger rigidly carried by said L-shaped lever; a draft link pivotally mounted on the carriage and connected to said recipro- 45

cating means; and a latch member carried by said draft link, engageable with said finger upon movement of the link in one direction to impart movement to said finger and L-shaped lever in a direction opposite to that imparted thereto by the boom-carried element.

4. In boom and bucket type distributing mechanism for concrete mixers, the combination with a boom supported by the mixer frame and subject to transverse tilting movements thereof, a bucket carriage mounted for longitudinal traverse on said boom, and a bucket pivotally connected to said carriage to accommodate relative movement between the two about an axis substantially longitudinal of the boom, said bucket having a discharge controlling door, of operating mechanism for said door comprising a portion mounted on said carriage, a portion mounted on the bucket and connected to the door, and pivotal connections between the two portions adjacent the pivotal connection between the bucket and carriage, said bucket-carried portion being subject to movements tending to undesirably open said door as a result of relative movement between the bucket and carriage about said longitudinal axis; and means for preventing such undesired opening of the door.

5. In boom and bucket type distributing mechanism for concrete mixers, the combination with a boom supported by the mixer frame and subject to transverse tilting movements thereof, a bucket carriage mounted for longitudinal traverse on said boom, and a bucket pivotally connected to said carriage to accommodate relative movement between the two about an axis substantially longitudinal of the boom, said bucket having a discharge controlling door, of operating mechanism for said door comprising a portion mounted on said carriage, a portion mounted on the bucket and connected to the door, and pivotal connections between the two portions adjacent the pivotal connection between the bucket and carriage, said bucket-carried portion being subject to movements tending to undesirably open said door as a result of relative movement between the bucket and carriage about said longitudinal axis; and resilient means included in the bucket-carried portion of said operating mechanism for counteract-

ing the movements thereof induced by said relative movements between the bucket and carriage, and thereby preventing such undesired opening of the door.

6. In boom and bucket type distributing mechanism for concrete mixers, a boom supported by the mixer frame; a bucket carriage mounted for longitudinal travel upon said boom; a bucket mounted by said carriage, having a discharge controlling door; a lever pivotally mounted on said carriage, having a latch engaging member; operating connections between said lever and door; draft links pivotally mounted on said carriage; a latch carried by said draft links arranged to co-operate with said engaging member to move said lever in one direction; means for oscillating said draft links upon their pivots; and a towing bracket mounted on said carriage, having spaced driving lugs arranged to provide lost motion driving connections with said draft links, whereby movement of said lever may be initiated in one direction by said latch and engaging member through lost motion movement of said links in one direction.

7. An element for control mechanism for the door of a concrete distributing bucket, comprising a substantially L-shaped lever having a journal at substantially the junction of the arms whereby it may be pivotally mounted, one of said arms being connectible through linkage with the door, and the other of the arms carrying members mounted intermediate its ends and at its free end for serial engagement with a resetting cam, said lever also having a latch-engaging finger extending therefrom laterally adjacent the second mentioned arm.

8. A towing member for the buckets of concrete distributing mechanism of the boom and bucket type, comprising a bracket rigidly attachable to the bucket assembly and having an up-standing web provided with a pair of laterally extending vertically converging separated lugs providing a space between for the reception of a pivoted draft link which may have alternate lost-motion engagement with said lugs as it is oscillated on its pivot.
